UNITED STATES PATENT OFFICE

GEORGE EUSTIS CORCORAN, OF NEW YORK, N. Y.

RUDDER

Application filed October 2, 1930. Serial No. 485,982.

This invention relates to apparatus for maneuvering various types of craft, and, while not necessarily restricted thereto, the same is particularly designed for use on watercraft, particularly the larger sizes of power vessels.

It is common knowledge that the rudder of a vessel begins to lose its efficiency below a predetermined speed and thereafter gradually loses its effectiveness to perform its function as a means for maneuvering the ship until it reaches a point of total ineffectiveness.

It is, therefore, the principal object of the present invention to provide a rudder equipped with auxiliary means for guiding and maneuvering a ship, even after the driving momentum has completely ceased, and this without in the slightest affecting the normal use of the rudder when the vessel is traveling at a speed where the rudder is fully efficient.

As a further object, the invention aims to provide an auxiliary guiding and maneuvering means for a ship which may be controlled coincident with or independent of the rudder, whereby to make for greater efficiency and more accurate maneuvering of a vessel, while in many instances eliminating the employment of tugs as an aid to the vessel, and in emergencies being useful in avoiding collisions.

Other objects of the invention reside in the provision of an improved rudder which is comparatively simple in its construction and mode of operation, inexpensive to produce and install, which may be adapted to practically any type of ship and which is highly efficient in its purpose.

With the above recited and other objects in view, reference is had to the following description and accompanying drawing, in which there is exhibited one example or embodiment of the invention, while the claims define the actual scope of the same.

Figure 1 is a fragmentary side view of the stern of a vessel equipped with a rudder constructed in accordance with the invention, parts being broken away and shown in section to disclose the underlying structure.

Figure 2 is an enlarged sectional plan view

taken approximately on the line indicated at 2-2 in Figure 1.

Figure 3 is a fragmentary vertical sectional view taken approximately on the line 3-3 of Figure 2.

Referring to the drawings by characters of reference, A designates the stern portion of the hull of a vessel provided with the usual propelling means B. The apparatus constituting the subject matter of the present invention which is designed for maneuvering the vessel includes a rudder 5 having a properly stream-lined external configuration to permit it to perform its function with the least amount of head resistance. The opposite sides of the rudder 5 are provided with recesses 6 and 7, within which are respectively mounted for rotation, propelling devices 8 and 9, such as the oppositely pitched screw propellers secured to axially aligned stub shafts 10 and 11 which extend inwardly through the opposite sides of the rudder. Suitable fluid tight stuffing boxes 12 and 13 are provided, through which the stub shafts 10 and 11 extend, and beveled pinions 14 and 15 are keyed to the inner ends of the stub shafts and located within the confines of the rudder. A beveled gear 16 meshes with the beveled pinions 14 and 15 and is secured to a drive shaft 17 which extends upwardly through the tubular rudder post or shaft 18. The upper end of the rudder post or shaft 18 has secured thereto a gear 19, with which a segment 20 meshes, to afford means for turning the rudder. The upper end of the drive shaft 17 extends above the upper end of the rudder post or shaft 18 and is connected to an independent motor 21 or equivalent means for rotating the drive shaft 17 in opposite directions for driving the propelling devices 8 and 9 in unison. In order to afford means for carrying away water from the leading propeller and for supplying water to the following propeller, a rear passageway 21 extends transversely through the rudder and establishes communication between the rear portion of the recesses 6 and 7. A pair of rearwardly diverging passageways 22 and 23 extends from a common port 24 in the leading edge of the rudder respec-

tively to the forward portions of the recesses 6 and 7. The passageways 22 and 23 and the port 24 also permit the water to freely pass therethrough to reduce head resistance when the rudder is in axial alignment with the ship.

In use and operation, when the vessel is traveling above a predetermined speed, the rudder 5 will function in its ordinary capacity without the aid of the propelling devices 8 and 9. When the vessel is traveling below a speed at which the rudder efficiently functions, the motive power for the propelling devices 8 and 9 is rendered active to drive said devices in the desired direction to properly maneuver the vessel. When the propelling devices are driven in one direction, they jointly act to exert a lateral traction in the desired direction to maneuver the ship. It is also apparent that the angle of the tractive force exerted may be varied by turning the rudder coincident with the driving of the propelling devices 8 and 9. It is further obvious that even when the vessel is motionless and has no way, the devices 8 and 9 may be employed to maneuver the craft. Due to the fact that the propelling devices 8 and 9 are disposed wholly within the confines of the rudder 5, it is apparent that no additional head resistance is offered, and with the propellers 8 and 9 at rest, the rudder will function in its usual capacity. In event of failure of the driving power for the propelling devices 8 and 9, it is apparent that the use of the rudder in its ordinary capacity is not affected.

From the foregoing, it will thus be seen that an apparatus has been devised for maneuvering a vessel, by virtue of which the same may be more accurately and effectually handled, especially at low speed, where the efficiency of the usual rudder is decreased. It is also within the province of the present invention to employ the device in many instances in lieu of a tug or tugs for docking a vessel and if not entirely eliminating the use of tugs, effecting a reduction in the number required.

While there has been illustrated and described a preferred embodiment of the invention, it is to be distinctly understood that no limitation is intended to the precise structural details, as variations and modifications which properly fall within the scope of the appended claims may be resorted to when desired.

What is claimed is:

1. An apparatus of the indicated character, having the combination of a rudder efficient to steer a ship at a predetermined speed and means within the confines of said rudder for exerting a thrust at an angle to the plane of the rudder to maneuver the ship independent of the rudder surfaces either when

traveling below said predetermined speed or having no way.

2. An apparatus of the indicated character, having the combination of a rudder efficient to steer a ship at a predetermined speed and means within the confines of said rudder for maneuvering the ship independent of the rudder surfaces either when traveling below said predetermined speed or having no way, said means including a propelling device adapted to exert a thrust at an angle to the plane of the rudder.

3. An apparatus of the indicated character, having the combination of a rudder efficient to steer a ship at a predetermined speed, means within the confines of said rudder for maneuvering the ship independent of the rudder surfaces either when traveling below said predetermined speed or having no way, said means including a propelling device adapted to exert a thrust at an angle to the plane of the rudder and means for driving the propelling device through the rudder post.

4. An apparatus of the indicated character, having the combination of a rudder efficient to steer a ship at a predetermined speed, means within the confines of said rudder for maneuvering the ship independent of the rudder surfaces either when traveling below said predetermined speed or having no way, said means including a propelling device adapted to exert a thrust at an angle to the plane of the rudder and means for reversibly driving the propelling device through the rudder post.

5. In an apparatus of the indicated character, a rudder having recessed opposite sides, propelling devices within said recessed portions, power transmission means within the rudder, means for reversibly driving said power transmission means located exteriorly of the rudder and extending through the rudder post.

6. A maneuvering apparatus for ships including a rudder having a tubular rudder post, recessed portions on the opposite sides of said rudder, axially aligned propelling devices within said recessed portions, power transmission means within the rudder and a drive shaft therefor extending through the rudder post and operatively connected with reversible driving means.

7. In an apparatus of the indicated character, a rudder having recessed opposite sides, propelling devices within said recessed portions, power transmission means within the rudder, means for reversibly driving said power transmission means located exteriorly of the rudder and extending through the rudder post, said rudder having a transverse passageway establishing communication between the recessed opposite sides.

8. In an apparatus of the indicated character, a rudder having recessed opposite sides,

propelling devices within said recessed portions, power transmission means within the rudder, means for reversibly driving said power transmission means located exteriorly of the rudder and extending through the rudder post, said rudder having a transverse passageway establishing communication between the recessed opposite sides and having rearwardly diverging passageways communicating with a common port in the leading edge of the rudder and respectively communicating with the recessed opposite sides thereof.

Signed at New York city in the county of New York and State of New York this 1st day of October, 1930.

GEORGE EUSTIS CORCORAN.
